UNITED STATES PATENT OFFICE.

JOHN D. TOMPKINS, OF VALATIE, NEW YORK.

METHOD AND APPARATUS FOR TREATING FIBROUS MATERIALS.

Application filed March 6, 1926. Serial No. 92,676.

The object of the invention is to enable wet fibrous material to be rapidly and economically dried, and although capable of other uses the invention has particular application to the drying of a paper web in the condition in which the latter is after being deposited on the forming wire or cylinder.

Other objects of the invention are to effect the drying of a web of the above nature without necessitating the application of high temperatures or excessive pressures thereto, preferably also in such manner that the fibres may be subjected to a bleaching action during the drying process.

The invention also aims to provide a device which will insure that the paper web follows along properly with a felt apron which is employed to carry it from the press rolls to the subsequent section of the machine.

Further objects and advantages of the invention will be in part obvious and in part specifically referred to in the description hereinafter contained, which, taken in conjunction with the accompanying drawings, discloses an apparatus constructed in accordance with the invention and adapted to carry out the processes which also constitute a part of such invention; such disclosure, however, is to be considered merely as illustrative of the principles of the invention. In the drawings:

Fig. 1 is a somewhat diagrammatic longitudinal sectional view of an apparatus adapted to carry out the invention.

Fig. 2 is a similar view showing a modified form of such apparatus.

If a web of paper as it comes from the web-forming parts of a paper making machine, is dried by the squeeze of press rolls in combination with a series of heated driers, the excessive pressure of the press rolls tends to injure the fibres, and the heated surfaces of the drying rolls particularly when the machine is run at high speeds, may require a high degree of heat in order to dry the web adequately; thus the fibre tendrils which make up the web may be too highly heated and rendered brittle.

In accordance with the present invention, fibrous material of the above nature is dried by subjecting the same to an electric current in conjunction with the forceful passage of air through the fibres, whereby the electricity tends to vaporize the moisture and

water, and the air passes through the material to conduct off the moist vapors as well as to absorb moisture itself directly from the fibre. The electric current also heats the web to some extent, due to the electric resistance of the latter, but the heat so generated may readily be kept below any value which would unduly heat the material; furthermore, the air current preferably is moderately heated, say, from 100° F. to 200° F. to promote the action of moisture liberation, but without involving temperatures which are high enough to injure the fibres in any way.

A web treated in the above manner may be dried sufficiently to enable the same to be run directly through the calenders, without the interposition of press rolls or drying rolls, although it will be understood that there is nothing to prevent the use of the invention in conjunction with press rolls or drying rolls if desired.

The present embodiment of the invention is illustrated as applied to a paper making machine having a forming wire 1 running between upper and lower couch rolls 2 and 3, whereby the fibres are deposited upon the forming wire 1 to form a web 4 which is carried along through the machine by felt aprons to calenders 6, and from thence to a suitable winding roller 7 or the like.

In the present instance the paper web is picked up from the forming wire 1 by means of an upper felt apron 8 which passes around a roller 9 located in advance of the upper couch roll 2, in such manner that the upper felt 8 supports the web and separates the same from the forming wire, and carries the web along into engagement with a lower felt apron 10, running over a roll 11 and guide rollers 12 and 13. It will be understood that the felt aprons 8 and 10 are provided with additional suitable guiding and supporting rolls which need not be described in detail.

The electric current is supplied by means of a suitable generator 15, one pole of which is electrically connected to the web 4, or one of the felt aprons associated therewith, as by means of a lead 16, branch conductors 17, and resilient contact fingers 18 which wipe against the web 4 or one of its felt aprons. In the present instance four of such contact fingers are illustrated, and circuit back to the generator is completed by

means of a lead 19 connected to the other pole of the generator, and also connected by means of branch conductors 20 to suction boxes 5 which are located in proximity to 5 the several contact fingers 18.

The potential of generator 15 need be no higher than is necessary to cause a flow of current across the resistance between contact fingers 18 and the suction boxes respectively adjacent thereto which are connected to branch conductors 20, such resistance being constituted by the fibres of the web 4, the felts 8 and 10 and the water carried thereby.

- 15 The sections of the web through which the electric current passes as above described, are also subjected to a current of air. In the present instance a current of air is caused to pass through the web 4 and upper felt 20 apron 8 by air blast pipes 21 located at points in the latter which are in the path of the electric current passing through the first contact finger 18 to felt apron 8, and while the web is still carried on the forming wire. 25 Thus the electric current tends to gasify a certain percentage of the water carried by web 4 and felt apron 8, and the air current carries off the same, as well as a certain amount of moisture which the air itself absorbs and takes away. Preferably the air 30 current is augmented by the suction boxes 5.

In a similar manner the web may be repeatedly subjected to the combined action 35 of a current of air and an electric current to dry the same; in the present embodiment of the invention, further suction boxes 5 are positioned beneath the lower felt apron 10 and air blast pipes 5 are associated therewith, whereby the paper web is successively 40 dried as above mentioned.

In the type of machine illustrated in Fig. 1 the paper web is then carried by the felt aprons 8 and 10 through upper and lower plain press rolls 22 and 23. It will be understood that the drying of the web by the combined action of the air currents and electric currents above described, will materially reduce the amount of water necessary to be extracted by the squeeze of the press rolls, thereby avoiding the necessity of excessive mechanical pressure which might injure the paper web, and gall it at the press rolls.

As shown, the upper felt apron 8 then carries the paper web along to a drier roll 23^a, said felt apron passing around a roller 24 which rests on the said drier roll 23^a to press the web into engagement therewith. The lower felt apron 10 also follows along with the upper felt apron for a short distance beyond the press rolls and passes around a blow roll 25, from within which a blast of air is directed on to the paper web 4 to insure that the latter will be carried along by and in contact with the upper felt apron 8. Thus the upper felt apron con-

tinuously carries along the paper web from the forming wire until the web is deposited upon the drier roll 23^a, or the first roll of the drier section of the machine.

During the extraction of water from the paper web as above described, a certain amount of nascent oxygen will be produced and serve as a bleaching agent for the fibres, the air current serving to carry off the gases through the body of the web immediately after their production, and thus permitting fresh oxygen to be generated to replace the same.

During the time that the paper web 4 is supported between the forming wire and felt 80 apron 8, the elimination of water through the agency of suction boxes 5, which are disposed underneath the forming wire, is aided by gravity, being in a downward direction, and, furthermore, the removal of water in 85 the above manner does not necessitate the bending of the paper web in such a way as to injure the bond between the newly deposited fibres, but it will be noted that the web travels along in a substantially flat condition 90 which does not destroy the bond. The suction boxes are also relatively inexpensive and require only a small amount of power, as compared to other devices such as suction 95 rollers, which latter would also require the bending of the paper web to make the suction effective.

Although the invention has been described as utilized for the treatment of a paper web, it will be understood that it is also applicable to the treatment of other fibrous sheet materials, such as textile or woven materials. Figure 2 illustrates an apparatus adapted for the treatment of fabrics in accordance with the invention. As shown in this figure a 100 sheet of wet fabric 5^a passes between an upper conveying apron 8^a carried by rolls 30 and 31 and a lower apron 10^a carried by rolls 32 and 33, such fabric being subjected to the combined action of an air-blast, preferably moderately heated, from air-blast pipes 24^a and suction boxes 34 cooperating with such air-blast pipes, as well as to the action of an electric current supplied from one pole of the generator 15^a through a lead 19^a, branch conductors 20^a to wipers 35, and by a lead 16 from the other pole of the generator, which is connected by suitable branch conductors 17^a to suitable metallic parts such as the suction boxes 34, for completing the 115 circuit from wipers 35 through the fabric sheet and back to the generator.

After having been bleached and dried in the above manner the fabric may then be passed over a suitable hot drum 36 and re-wound upon a roll 37.

This application contains certain subject matter disclosed in my prior application Serial Number 646,054, filed June 18, 1923, renewed March 2nd, 1926, entitled "Method 130

and apparatus for drying fibrous materials."

While certain specific embodiments of the invention have been described, it will be obvious that many changes may be made there-in without departing from its spirit as defined in the appended claims.

I claim:

1. The process of treating fibrous sheet material which comprises subjecting the same to the combined action of an electric current and a current of air passing through said material.

2. The process of treating a paper web which comprises subjecting the same to the combined action of an electric current and a current of air passing through said web.

3. The process of treating a paper web which comprises supporting and advancing the same by a felt apron and subjecting the moving felt apron and paper web to the combined action of an electric current and an air current.

4. The method of treating a paper web which comprises drying the same by successive applications of an electric current and an air current.

5. An apparatus for treating fibrous materials, which comprises means for advancing a web of such material along a path, means for conducting an electric current across such path, together with means for producing a current of air across said path adjacent the point of travel of said electric current thereacross.

35. 6. A paper making machine comprising a felt apron adapted to carry along a wet fibre web, electrically conducting members disposed on opposite sides of said web adapted to cause an electric current to pass across the felt apron and the web carried thereby, and means for producing a current of air passing through the felt apron and web adjacent said conducting members.

7. A paper making machine comprising a suction device, a felt apron adapted to contact with a paper web adjacent said device, and means for conducting an electric current

to said felt apron and web adjacent said suction device.

8. A paper making machine comprising a suction device, a felt apron adapted to contact with a paper web adjacent said device, means for conducting an electric current to said felt apron and web adjacent said suction device, and means for projecting air under pressure through said felt apron toward said suction device.

9. A paper making machine comprising upper and lower felt aprons adapted to advance a paper web therebetween, a suction roll in contact with one of said felt aprons, and means for conducting an electric current through said felt aprons adjacent said roll.

10. A paper making machine comprising upper and lower felt aprons adapted to advance a paper web therebetween, a suction device in contact with one of said felt aprons, means for conducting an electric current through said felt aprons adjacent said device, and means for projecting air under pressure through both of said felt aprons toward said suction device.

11. The process of drying and bleaching fibrous material which comprises subjecting the same to the combined action of an electric current and a current of air passing through said material.

12. The process of treating a paper web which comprises subjecting the same to the combined action of an electric current and a current of air passing through said web while the web is carried upon the forming wire.

13. The process of treating a paper web which comprises subjecting the same to the combined action of an electric current and a current of air passing through said web while the paper web is carried between the forming wire and a felt apron.

In testimony that I claim the foregoing, I have hereunto set my hand this 24th day of February, 1926.

JOHN D. TOMPKINS.
